UNITED STATES PATENT OFFICE.

WALTER EASTER HASKIN, OF NEW YORK, N. Y., ASSIGNOR TO PRESSED & WELDED STEEL PRODUCTS COMPANY, OF LONG ISLAND CITY, NEW YORK, A CORPORATION OF NEW YORK.

BOOKSTAND.

Application filed January 12, 1927. Serial No. 160,681.

This invention relates to bookstands, an object of the invention being to provide a bookstand which is designed to conveniently hold a series of books, such as telephone books and the like, and enable any book to be swung readily to open position without disconnecting the same from the stand.

A further object of the invention is to provide a mechanism in which a plurality of books may be conveniently assembled, supported and partially enclosed, so that these books may be referred to as frequently as desired without any danger of losing the books or misplacing them.

15 A further object is to provide a bookstand of this character which may be supported on a table, desk or other part, or may be secured to a wall or vertical support and function with equal facility in either position.

20 With these and other objects in view, the invention consists in certain novel features of construction and combinations and arrangements of parts, which will be more fully hereinafter described and pointed out in the 25 claims.

In the accompanying drawings—

Figure 1 is a perspective view showing my improved bookstand arranged to be supported on a table, desk or other support;

30 Figure 2 is a similar view, showing one of the books open and in position for reading or examining the same;

35 Figure 3 is a perspective view showing my improved stand with the parts in position for securing the same to a wall or other upright support;

Figure 4 is a view in front elevation of the device shown in Figure 1, with a portion thereof broken away;

40 Figure 5 is a fragmentary detail showing the construction of the rod ends.

The device will be first described with the parts assembled so that the device is adapted to rest upon a table or other support and then 45 we will indicate how the parts may be changed to arrange them for securing them to a wall or other upright support.

A, A represent a pair of uprights. These uprights are composed of sheet metal. Each 50 upright has an outer plate 1 and an inner plate 2 spaced apart. Each pair of plates are connected at both front and rear by plates 4 and at the front only by plates 3, the latter being normally at the bottom of the supports.

The supports therefore constitute uprights 55 which are open at their upper ends and at their front and rear portions.

Vertically disposed plates 5 are located within the uprights A, A and adjacent the outer plates 1, 1, and have laterally projecting 60 flanges 6 which constitute book rests. These uprights A, A are connected by a plurality of rods 7, and spacing plates 8 are supported on the rods and are located between binders 9, holding the binders apart and these binders 65 are pivotally mounted on a rod 10 so that the binders are free to swing from one position to another. When in one position the binders have their end portions resting against certain of the rods 7 and are mainly enclosed 70 in the structure above defined, one binder being partially enclosed in each upright and the other binders being located between the first-mentioned binders and spaced apart by the plates 8.

To hold the parts in rigid position after they are once assembled nuts 12 are screwed onto the outer ends of the rods 7 and 10 and each of these rods is made with a shoulder 11 adapted to bear against the plates 5, 5, and 80 prevent lateral or independent movement of any of the parts when the nuts are secured onto the rods.

The binders 9 are pivotally mounted on the rods 10 at a point or points nearer one end of 85 the binder than the other, so that when the binders are swung outwardly into position to permit access to the books, as indicated in Figure 2, the ends of the binders will rest upon the upper front rod 7, and the laterally 90 projecting flanges 6 will serve to support the leaves of the end binders when the latter are in open position.

When the device is to be arranged for supporting the same on a wall or other structure, 95 as indicated in Figure 3, it is simply necessary to remove the rods, give the plates 5, 5 a position so as to engage over other corners of members A, A, which is a ninety degree change of position, and then reassemble the parts with 100 the rods in place, as indicated in said figure, when the structure will be precisely as before except that the members A will have a position at a different angle to the binder supporting parts and can be secured to a wall or 105 upright in any approved manner.

In the upper left-hand corner of each support A, shown in Figures 1 and 2, a nut 12' is

illustrated, which is connected to a short bolt extending only through the plate 5 and outer plate 1, as at this point the rod cannot be used as it would interfere with the movement of the 5 binders. When the parts are arranged for securing the same to a wall this bolt and nut are shifted to the position shown in Figure 3.

While I have illustrated what I believe to be a preferred embodiment of my invention, it 10 is obvious that various changes and alterations might be made in the general form of the parts described without departing from my invention and hence I do not limit myself to the precise details set forth but consider myself 15 at liberty to make such changes and alterations as fairly fall within the spirit and scope of the appended claims.

I claim:

1. A bookstand, including a pair of hollow 20 supporting members spaced apart, rods connecting said supporting members, a book holder normally having its back portion exposed and pivotally connected between its ends to one of said rods whereby a book supported by said holder when in normal position rests upon other of said rods, and a pivotal movement of said book holder moves the book supported thereby from a position between the supporting members and permits 25 the book to be opened and supported upon its pivot and other parts of said bookstand.

2. A bookstand, including a pair of hollow 30 supporting members spaced apart, rods connecting said supporting members, a plurality

of book holders normally having their back 35 portions exposed and pivotally supported on one of said rods and adapted when swung from normal position to be supported on another of said rods, and when in said last position permitting a book held by said holder 40 to open and rest upon a portion of said stand but supported mainly by said holder on its pivot.

3. A bookstand, including a pair of supports, a plurality of rods connecting the supports, book holders normally having their back portions exposed and pivotally mounted on one of the rods, spacing plates supported by the rods between the book holders, and other plates located within the supports and having laterally projecting flanges constituting supports for the book holders when the latter are 45 swung to open position.

4. A bookstand, including a pair of supports, a plurality of rods connecting the supports, book holders normally having their back portions exposed and pivotally mounted on one of the rods, spacing plates supported by the rods between the book holders, and other plates located within the supports and having laterally projecting flanges constituting supports for the book holders and books when the latter are swung to open position, 50 said supports, rods and plates removably coupled so that the angular disposition of the plates relative to the supports may be varied and the bookstand secured to a wall.

WALTER EASTER HASKIN
